DESIGN FOR A BELT

Jacob Lewis Bibula, New York, N. Y.

Application September 16, 1938, Serial No. 79,927

Term of patent 3½ years

To all whom it may concern:

Be it known that I, Jacob Lewis Bibula, a citizen of the United States of America, residing in the city of New York, county of New York, and State of New York, have invented a new, original, and ornamental Design for a Belt, of which the following is a specification, reference being had to the accompanying drawing, forming part thereof.

The figure on the drawing is a front perspective view of a belt showing my new design.

I claim:

The ornamental design for a belt, substantially as shown.

JACOB LEWIS BIBULA.
